A. D. PUFFER, OF SOMERVILLE, MASSACHUSETTS.

Letters Patent No. 86,861, dated February 9, 1869.

IMPROVEMENT IN BEER-FAUCETS.

The Schedule referred to in these Letters Patent and making part of the same

To all whom it may concern:

Be it known that I, A. D. PUFFER, of Somerville, in the county of Middlesex, and State of Massachusetts, have invented an Improvement in Faucets, or Draught-Cocks; and I do hereby declare that the following, taken in connection with the drawings which accompany and form part of this specification, is a description of my invention, sufficient to enable those skilled in the art to practise it.

This improvement has particular reference to the construction of faucets to be used in connection with that class of beer-pumps, soda-apparatus, &c., in which the draught-cocks are made with a handle, placed over the centre of the faucet, and swinging down in front of the same, so as to have an ornamentation, or symmetry of design, suitable for counters or saloons; and my invention relates to the construction of the handle for operating the plug or valve of such draught-cock.

The plug, or valve, extends horizontally through the head of the faucet, and the handle is bifurcated, having two arms secured, respectively, to the opposite ends of the plug, and uniting at the point where the handle is to be worked by hand; and

My invention consists in making this handle of two independent parts, each secured, at one end, to one end of the plug, by a suitable screw-fastening, and both united and confined together at their opposite ends by a suitable sleeve or screw-nut.

The drawings represent a faucet embodying my improvement.

A shows a side elevation of the faucet.

B is a vertical section in the line x x.

a denotes the horizontal body, or barrel, of the faucet, having, at its rear end, a screw b, by which it is fastened to the liquid-containing vessel, and, at its opposite end, an eduction-tube, c, through which the liquid is drawn.

d denotes the plug, or valve, extending through the head e, and controlling the passage from the tube a into the tube c.

f denotes the handle by which the plug is operated.

The two parts of the handle are respectively denoted by the letters g h, each being composed of a vertical stem, i i', with an arm, k k', branching therefrom, as seen at B.

The lever-end of each arm, k, is made with a ring, l,

which slips over the end of the plug, (as seen at B,) the arm, at one end of the plug, being screwed up against a shoulder, m, on the plug, by a screw, n, (a flange on the head of which abuts against the ring l,) and the arm at the opposite end being screwed up against a spring, o, by a similar screw, p, the spring abutting against the head e, and the flange of the screw against the ring.

Each stem, i i', is made semi-cylindrical, or slightly conical, and each has, at its lower end, a half screw-thread, q, and, at its upper end, a half screw-thread, r, the two threads, q q, when brought together, forming a screw, upon which is placed a nut, s, and the two threads, r r, a screw, over which is placed a screw-cap, t, the cap t screwing down against a sleeve, u, which is dropped upon the nut s, as seen at A and B.

The nut s may be dispensed with, but I prefer to use it.

In putting the faucet together, the plug, or valve d, is first passed through the head e, and the ring at the end of the arm i is then slipped upon and secured to the large end of the plug by the screw n; (or this arm may be applied before insertion of the plug.)

The spring o is then slipped upon the opposite end of the plug, and the ring of the arm k' is slipped over the end of the plug, and is screwed up against the spring by the screw p.

The two stem-pieces, i i', being then brought together, the nut s is screwed down over the threads q, the sleeve u is dropped upon the stem, and the cap t is screwed down upon the top of the stem.

As will be readily seen, this forms a strong and substantial handle, which remains perfectly fast to the plug, which can be readily dismembered for removal of the plug, and which forms an ornamental lever, or handle, for operating the plug, standing centrally over the head of the faucet.

I claim a faucet, having a handle for operating the plug, or valve, made in two parts, fastened, at their lower ends, to the opposite ends of the plug, and united, at their upper ends, substantially as described.

A. D. PUFFER.
